UNITED STATES PATENT OFFICE.

ROBERT A. HATHHORN, OF HOUSTON HEIGHTS, TEXAS.

ELEVATOR.

1,191,421.

Specification of Letters Patent. Patented July 18, 1916.

Application filed March 12, 1915. Serial No. 13,904.

To all whom it may concern:

Be it known that I, ROBERT A. HATHHORN, a citizen of the United States, residing at Houston Heights, in the county of Harris 5 and State of Texas, have invented certain new and useful Improvements in Elevators, of which the following is a specification.

This invention relates to new and useful improvements in elevators.

10 The object of the invention is to provide an elevator of the character described equipped with a locking device, whereby the elevator car will be automatically locked against movement in case the cable supporting the same should become broken, and the car is thus prevented, in such an event, from dropping to the bottom of the shaft.

With the above and other objects in view, the invention has particular relation to certain 20 novel features of construction, operation and arrangement of parts, an example of which is given in this specification and illustrated in the accompanying drawings, wherein:

25 Figure 1, shows a front elevation of the elevator. Fig. 2, shows a fragmentary vertical sectional view, taken on the line *a—a*, of Fig. 1. Fig. 3, shows a horizontal sectional view, taken on the line *c—c* of Fig. 1, and Figs. 4 and 5, show, respectively, a side elevation and an edge view of the locking wedge employed.

Referring now more particularly to the drawings, wherein like numerals of reference designate similar parts in each of the figures, the numerals 1, 1, refer, respectively, to the vertical tracks, which are spaced apart and arranged on opposite sides of the elevator shaft and are fixed in their relation to 35 each other in any well known manner. The car which moves on this track, may be of any desired construction. As shown, it includes, the upper and lower transverse beams 2 and 3, which are fixed in their relation to one another by the side bars 4, 4, and the beam 3, supports the platform 5, forming the floor of the elevator car. The facing sides of the track 1, 1, are abruptly offset from each edge, forming the ribs 6, 6, 45 whose edges have upwardly inclined ratchet teeth, forming the ratchet faces 7, 7, and these ribs each have vertically extending guides 8, 8, abruptly offset relative to their respective ribs, and the corresponding ends 50 of the beams 2 and 3 are bifurcated, the inner side of their fingers being shaped to con-

form to and embrace said ribs 6 and guides 8, and to move up and down thereon. Depending from the beam 2, at each end are two bearing members 9, 9, arranged on opposite sides thereof.

Two levers 10, 10, are provided, whose inner ends are adjacent, but whose outer ends are bifurcated, forming the resilient fingers 11, 11, which are pivoted to the lower 60 ends of the corresponding bearing members 9, 9. Two resilient members 12, 12, are employed, having their upper ends secured to the beam 2, and their other ends pressing downwardly against the inner ends of the 65 respective levers 10, 10. A plate 13, having upturned sides, is attached to the lower end of the lifting cable 14, and this cable passes up between the adjacent ends of the levers 10, 10, and said plate engages underneath 70 the inner ends of said levers and the car is sustained thereby, said levers resting against the beam 2.

Secured to the free ends of the respective fingers 11, are the locking wedges 15, in 75 alinement with the ratchet faces 7, and a resilient strap as 16, has its upper end secured to each of the wedges 15, and the lower ends of these straps are secured to similar locking wedges 15', also in alinement 80 the ratchet faces 7. The inner sides of the wedges 15, 15', have ratchet teeth, but they are normally held out of engagement with the opposing ratchet faces 7, by reason of the resiliency of their supporting 85 fingers 11, and supporting straps 16. The upper ends of the wedges 15, 15', are beveled, being wedge shaped, as stated and the inner sides of the opposing fingers of the bifurcated ends of the beams 2 and 3, are 90 correspondingly beveled. When the car is in motion, it is sustained by the cable 14, and the inner ends of the levers 10, 10, rest against the under side of the beam 2, operating to lower the free end of the fingers 100 11, and the wedges 15, carried thereby, which in turn, operate through the straps 16, to lower the wedges 15', and said wedges 15 and 15', are disengaged from the opposing fingers of the beams 2 and 3, and by the 105 resiliency of the fingers 11, and straps 16, are carried out of engagement with their opposing ratchet faces 7 and the car is permitted to move freely. Should the cable 14, become broken, the springs 12, 12, will immediately operate to lower the inner sides 110 of the levers 10, 10, which, through the

mechanism just described, will operate to elevate the wedges 15, 15', into contact with the sloping faces of the inner sides of the opposing fingers, and said wedges will be 5 clamped against and engage with the faces 7, and will lock the car against movement automatically. The lower ends of the strap 16, have oblong slots 17, through which pass the respective pins 18, which are secured to 10 the beam 3. These pins hold the lower ends of the straps 16, in position, but do not interfere with their vertical movement.

I have shown only one form of this device, but it is obvious that the mechanical 15 structure thereof may be varied without departing from the principle of the invention, and I hereby reserve the right to make such structural modifications, so long as I keep within the scope of the appended claims.

20 1. What I claim is:

1. A device of the character described including opposing vertical tracks fixed in their relation to one another, vertical ribs carried by the facing sides of said tracks, whose opposite edges are provided with upwardly inclined ratchet teeth, a pair of cross beams spaced apart and fixed in their relation to each other, whose ends are bifurcated forming fingers which embrace the corresponding 25 ribs, bearing members depending from the respective ends of the upper beam, a pair of levers, whose inner ends are adjacent and whose outer ends are bifurcated, forming resilient fingers, which are pivoted to the 30 lower ends of said corresponding bearing members, resilient members pressing downwardly against the inner ends of said levers, a plate having upturned sides underneath the adjacent ends of said levers, a cable sustaining 35 said plate, locking wedges whose inner sides have ratchet teeth secured to said resilient fingers, resilient straps depending from each of said wedges, similar locking wedges carried by the lower ends of said 40 straps, said wedges resting against the inner sides of the corresponding fingers of said beams and being forced inwardly thereby as they are elevated and being thus locked with the ratchet teeth of said ribs.

45 2. A device of the character described including opposing vertical tracks fixed in their relation to each other, whose opposite edges are provided with ratchet teeth, a pair of cross beams spaced apart and fixed in

their relation one above the other, whose 55 ends are bifurcated forming fingers which embrace the corresponding tracks, an elevator car supported by said cross beams, a pair of levers pivoted relative to the upper beam whose inner ends are adjacent and 60 whose outer ends are bifurcated forming resilient fingers, resilient members pressing downwardly against the inner ends of said levers, a plate underneath the adjacent ends of said levers, a cable sustaining said plate, 65 locking wedges whose inner sides have ratchet teeth secured to said resilient fingers, resilient straps depending from each of said wedges, similar locking wedges carried by the lower ends of said straps, said wedges 70 resting against the inner sides of the corresponding fingers of said beams and being forced inwardly thereby as they are elevated and being thus locked with the ratchet teeth of said tracks.

75 3. A device of the character described including opposing vertical tracks fixed in their relation to each other, whose edges are provided with ratchet teeth, a pair of cross beams spaced apart whose ends are bifurcated forming fingers which embrace the corresponding tracks, an elevator car supported by said cross beams, a pair of levers pivoted relative to the upper beam whose inner ends are adjacent and whose outer ends are bifurcated forming resilient fingers, resilient members pressing downwardly against the inner ends of said levers, a means 80 engaging underneath the adjacent ends of said levers, a cable sustaining said means, locking wedges whose inner sides have ratchet teeth secured to said resilient fingers, resilient members depending from each of said wedges, similar locking wedges carried by the lower ends of said members, said 85 wedges resting against the inner sides of the corresponding fingers of said beams and being forced inwardly thereby as they are elevated and being thus locked with the ratchet teeth of said tracks.

90 100 In testimony whereof I have signed my name to this specification in the presence of two subscribing witnesses.

ROBERT A. HATHHORN.
